SOUND RECORDING APPARATUS

Glenn L. Dimmick, Haddonfield, N. J., assignor
to Radio Corporation of America, a corpora-
tion of Delaware

Application March 31, 1939, Serial No. 265,278

9 Claims. (Cl. 179—100.3)

This invention relates to sound recording apparatus, and more particularly to apparatus for the photographic recording of sound on film by the variable density method. The subject matter of the present application is an improvement on the apparatus of my Patent No. 2,095,317, issued October 12, 1937, and on the joint application of J. L. Underhill and myself, Serial No. 210,592, filed May 28, 1938. In the aforesaid patent, an apparatus is described and claimed for recording sound by means of a penumbra or shadow of variable intensity which is cast by a fixed mask. In the said joint application, a modification of the apparatus is described and claimed wherein a movable penumbra mask is provided which is moved in accordance with the envelope of the sound wave currents in order to provide ground noise reduction.

In the apparatus according to the present invention, I provide means for correcting the quantity of light impressed upon the film at different positions of the galvanometer mirror so as to compensate for the characteristic curves of the negative or positive film, or both, or for compensating for any other non-linear effect which may be produced, such, for example, as non-linearity of the amplifier or the like. I accomplish this result by the insertion of a mask having an aperture of variable area adjacent the objective lens or mirror or filament of the recording optical system. The area of the mask is so adjusted as to produce the necessary correction or compensation in the quantity of light transmitted to the film without affecting the area of the image upon the film.

One object of the invention is to provide an improved sound recording optical system.

Another object of the invention is to provide an improved record optical system which will be readily adjusted to compensate for irregularities in photographic characteristic or other non-linear characteristics.

Another object of the invention is to provide an improved optical system of the penumbra type wherein the brightness of the image cast upon the film may be adjusted as desired.

Other and incidental objects of the invention will be apparent to those skilled in the art from a reading of the following specification and an inspection of the accompanying drawings in which:

Figure 1 is a schematic perspective view of an optical system constructed in accordance with the present invention;

Figure 2a is a view of the slit with the penumbra

image in one position thereon and Figure 2b shows the filament image in the galvanometer as it appears in the position 2a of the penumbra on a slit;

Figure 2c shows the penumbra image in a second position in relation to the slit and Figure 2d shows the filament image in the galvanometer mirror as it appears in the second position of the penumbra;

Figure 2e shows the penumbra in a third position in relation to the slit and Figure 2f shows the galvanometer mirror as it appears from the slit in the third position;

Figure 3a shows a graph of light intensity plotted against galvanometer deflection using a rectangular galvanometer mirror and a mask having a rectangular aperture;

Figure 3b shows a graph of light intensity plotted against galvanometer deflection using a triangular mirror or mask shape;

Figure 4 is a typical H and D curve showing log exposure plotted against print density;

Figure 5 is a graph showing transmission of the sound record print plotted against the exposure of the negative required to produce that transmission and illustrating the type of error which must be compensated for;

Figure 6 is a graph showing negative exposure required to produce a linear print plotted against the galvanometer deflection;

Figure 7 shows print transmission plotted against galvanometer deflection for a print produced from a negative recorded with the optical system corrected as shown in Fig. 6; and

Figure 8 shows the shape of mask required to produce the correction indicated in Fig. 6.

Referring first to Fig. 1, the usual recording lamp filament is indicated at 10. Light from the lamp 10 passes through the condenser 11 to the rectangular mask 12 and thence to the movable penumbra mask 13, which may be moved in accordance with the envelope of the sound waves as described in the Underhill et al. application supra. An additional penumbra mask 14 is provided at the extreme limit of desired movement of the mask 13 so that the mask 13 may move beyond the optical limiting point without further affecting the image produced.

Light passing the masks 13 and 14 is directed by the lens 15 to the galvanometer mirror 16 which is adapted to be vibrated in accordance with the sound waves to be recorded. The focal lengths of the lenses 11 and 15 are so chosen that the lamp filament 10 is imaged in the mirror 16. The lens 17 directs light from the galvanom-

eter mirror 16 through the slit 19 in the slit plate 18 and through the mask 20 having the aperture 21 onto the objective lens 22. The lens 17 is of such focal length that a real image of the galvanometer mirror 16 is formed in the plane of the mask plate 20 which is substantially in the plane of the entrance pupil of the objective 22. The objective 22 may, of course, be composed of a plurality of lenses with the mask 20 closely adjacent the first of the lenses. The objective 22 is of such focal length as to form a sharp image of the slit 19 upon the film 23.

It will be apparent from the above stated relation of the several elements of the optical system that, as considered from the image on the film 23, the mask plate 20 with its aperture 21 is located at an aperture stop of the system, the slit 19 which is quite small is located as an image stop, the galvanometer mirror 16 is located as a second aperture stop, the penumbra mask 13 is located as a third aperture stop and the mask 12 is located as a second image stop. The aperture stops affect the brightness of the image on the film 23 without affecting its size or position; whereas, the image stops serve to define the size and position of the image, the slit 19 defining the position of the final image on the film 23 and the stop 12 defining the intermediate image upon the slit plate 18.

The relation of these stops may be better understood by reference to Figs. 2a to 2f. When the penumbra is in the position shown in Fig. 2a and the image of the aperture stop in the plate 35 12 is in the position indicated at 24 in Fig. 2a the slit 19 receives the full brightness from the filament 10 and if the galvanometer mirror 16 is viewed through the slit 19, it will appear as shown in Fig. 2b, the galvanometer mirror being substantially filled with the filament image and the entire height of the filament image being visible in the galvanometer mirror.

If the penumbra image is moved to the position shown in Fig. 2c where the image of the aperture stop 12 occupies the position shown at 24 in this figure in relation to the slit 19, the light intensity on the slit will only be half that which occurs in Fig. 2a. If, in this position, the galvanometer is viewed through the slit, it will appear as shown in Fig. 2d, only half of the filament image being visible in the galvanometer mirror, and this filling only half of the mirror area.

If the galvanometer mirror 16 is further tilted until the penumbra is completely off the slit 19, as shown in Fig. 2e, then observation through the slit will show the galvanometer mirror as indicated in Fig. 2f with no light being directed from the galvanometer mirror to the slit and with none of the filament image being apparent. This effect is partly due to the narrow width of the slit 19 since an aperture at this point of a considerable area would permit light to pass from the other portions of the shadow; or it might be stated that the slit serves to scan the penumbra image as it moves up and down.

If the aperture plate 20 were omitted or if a rectangular aperture were provided therein similar to the aperture in the plate 12, then the light intensity as varied by deflection of the galvanometer mirror would follow the curve shown in Fig. 3a, which shows that the light intensity varies linearly with the galvanometer deflection from minimum to maximum intensity.

If a triangular mirror or triangular mask were

substituted as shown in Fig. 3b, then the light intensity reaching the film would vary as the square of the galvanometer deflection substantially as shown in the curve of light intensity plotted against galvanometer deflection in Fig. 3b.

If a typical film stock such as is used for making sound picture prints is exposed to light of different intensities and developed, and the density is plotted against the exposure as in the conventional H and D curve, a curve such as shown in Fig. 4 will result; i. e., Fig. 4 represents a typical H and D curve for positive stock. It will be apparent from this curve that if the light to be transmitted by the print onto the photocell in reproduction is to be a linear function of galvanometer deflection, then the light transmitted to the film for its exposure must not be a linear function of galvanometer deflection as shown in Fig. 3a, but must vary inversely to the shape of the curve shown in Fig. 4. The negative film stock on which the original recording is made will likewise have a characteristic curve somewhat similar to Fig. 4, but since the points of greatest transmission on the negative are those of least transmission on the print and vice versa, the negative curve will produce a curvature of print density or transmission which is inverted in respect to the print curve.

The composite of the negative and print curves is shown in Fig. 5, where the transmission of the print is plotted against the exposure of the negative. It will be apparent that in order to secure a substantially linear print transmission in relation to galvanometer deflection, the light must be so varied in relation to galvanometer deflection to produce a curve which is substantially complementary to the curve shown in Fig. 5 and such a curve is shown in Fig. 6, where the galvanometer deflection is plotted against the required negative exposure for a substantially linear print transmission.

In Fig. 7 the galvanometer deflection is shown as plotted against print transmission when corrected in the manner shown in Fig. 6, and it will be apparent that a substantially linear relationship results.

In order to accomplish the foregoing substantially linear relationship between galvanometer deflection and print transmission, I insert the mask 20 having the aperture 21 as shown more accurately in detail in Fig. 8. This aperture 21 is designed in accordance with the required negative exposure as indicated in Fig. 6.

Since the mask 21 is located at the entrance pupil of the objective 22 and the galvanometer mirror 16 is imaged thereon, the image on the mask 20 will vary in the manner indicated in Figs. 2b, 2d and 2f. It will be apparent that at the upper end of the aperture, which is relatively narrow, only a small amount of light will be transmitted from the filament, while at the lower portion, which is broader, a greater amount of light will be transmitted and by properly shaping this aperture, the light transmitted from the galvanometer for any given deflection will correspond substantially with the curves shown in Fig. 6.

It will be apparent that any movement of the mask 13 will produce a shifting in the portion of the filament visible on the mask plate 20 in the same manner as will movement of the galvanometer mirror 16 and that, therefore, the correction of exposure will remain constant whether the exposure be varied by the galvanometer 16 or by the mask 13.

It will be apparent to those skilled in the art that a mask of variable density may be substituted for the aperture plate 20 and will accomplish the same result, but I prefer to use the variable area mask because the shape of the aperture may be readily changed as required to accommodate emulsions of different characteristics, and the shape of the aperture may be readily calculated or plotted from a curve of print transmission determined in the manner above described.

It will also be apparent that the mask may be located at any of the other aperture stops of the system, as, for example, at the galvanometer mirror or adjacent the filament of the light source.

Having now described my invention, I claim:

1. In a sound recording optical system of the penumbra type having an objective, a mask having light transmission varying along the direction of movement of the light beam located at the entrance pupil of the objective.

2. A sound recording optical system including an exciter lamp, means for directing a beam of light from said exciter lamp to a means for deflecting the beam in accordance with sounds to be recorded, a penumbra mask between said lamp and said deflecting means, means having a narrow slit therein between said deflecting means and the sound recording position, an objective for imaging said slit upon a film at the sound recording position, and a mask having a transmission varying along the direction of deflection of said beam located substantially at the entrance pupil of said objective.

3. A sound recording optical system including an exciter lamp, means for directing a beam of light from said exciter lamp to a means for deflecting the beam in accordance with sounds to be recorded, a movable penumbra mask between said lamp and said deflecting means, means having a narrow slit therein between said deflecting means and the sound recording position, an objective for imaging said slit upon a film at the sound recording position, and a mask having a transmission varying along the direction of deflection of said beam located substantially at the entrance pupil of said objective.

4. A sound recording optical system including an exciter lamp, means for directing a beam of light from said exciter lamp to a galvanometer for deflecting the beam in accordance with sounds to be recorded, a penumbra mask between said lamp and said deflecting means, means having a narrow slit therein between said deflecting means and the sound recording position, an objective for imaging said slit upon a film at the sound recording position, and a mask having a transmission varying along the direction of de-

fection of said beam located substantially at the entrance pupil of said objective.

5. A sound recording optical system including an exciter lamp, means for directing a beam of light from said exciter lamp to a galvanometer for deflecting the beam in accordance with sounds to be recorded, a penumbra mask between said lamp and said deflecting means, a slit plate having a narrow slit therein between said deflecting means and the sound recording position, an objective for imaging said slit upon a film at the sound recording position, and a mask having a transmission varying along the direction of deflection of said beam located substantially at the entrance pupil of said objective.

6. A sound recording optical system including an exciter lamp, means for directing a beam of light from said exciter lamp to a means for deflecting the beam in accordance with sounds to be recorded, a penumbra mask between said lamp and said deflecting means, means having a narrow slit therein between said deflecting means and the sound recording position, an objective for imaging said slit upon a film at the sound recording position, and a mask having an aperture having a transmission varying along the direction of deflection of said beam located substantially at the entrance pupil of said objective.

7. In combination with a sound recording optical system of the penumbra type having a light source, an objective for directing a narrow line of light upon the film, a plurality of lenses for directing light from said source to said objective, and means for deflecting the light beam in accordance with sound to be recorded, a mask having light transmission varying along the direction of deflection of the light beam.

8. In combination with a sound recording optical system of the penumbra type having a light source, an objective for directing a narrow line of light upon the film, a plurality of lenses for directing light from said source to said objective, and means for deflecting the light beam in accordance with sound to be recorded, a mask having light transmission varying along the direction of deflection of the light beam and located at one of the aperture stop positions of the system.

9. In combination with a sound recording optical system of the penumbra type having a light source, an objective for directing a narrow line of light upon the film, a plurality of lenses for directing light from said source to said objective, and means for deflecting the light beam in accordance with sound to be recorded, a mask having light transmission varying along the direction of deflection of the light beam and located adjacent said deflecting means.

GLENN L. DIMMICK.
